US0D1073050S

(12) **United States Design Patent** (10) **Patent No.:** **US D1,073,050 S**
(45) **Date of Patent:** **** Apr. 29, 2025**

(54) **WAIST-MOUNTED FAN**

(71) Applicant: **Shaojun Wu**, Jiangxi (CN)
(72) Inventor: **Shaojun Wu**, Jiangxi (CN)
(**) Term: **15 Years**
(21) Appl. No.: **29/984,935**
(22) Filed: **Jan. 15, 2025**
(51) LOC (15) Cl. **23-04**
(52) U.S. Cl.
USPC **D23/370**
(58) **Field of Classification Search**
USPC D23/333, 332, 335, 355, 364, 370, 377,
D23/381, 382
CPC F04D 29/522; F04D 29/644
See application file for complete search history.

Assistant Examiner — Andrea Marie McKay

(57) **CLAIM**

The ornamental design for a waist-mounted fan, as shown and described.

DESCRIPTION

FIG. 1 is a front, left and top perspective view of a waist-mounted fan showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 1.

The broken lines depict portions of the waist-mounted fan that form no part of the claimed design. The dash-dot-dash broken lines are for notating enlarged views and form no part of the claimed design.

1 Claim, 9 Drawing Sheets
